[57] CLAIM

The ornamental design for a jewelry display cabinet, substantially as shown and described.

DESCRIPTION

FIG. 1 is a front elevational view of a jewelry display cabinet showing my new design, it being understood that the cabinet has the same appearance in rear elevation;

FIG. 2 is a side elevational view thereof, it being understood that the cabinet has the same appearance from either side;

FIG. 3 is a top plan view thereof;

FIG. 4 is a bottom plan view thereof, and

FIG. 5 is a section taken on line 5—5 of FIG. 1.
